[57] ABSTRACT

A new and distinct cultivar of African violet named Little Shoshone Girl characterized by its mid-size growth habit (13-15 cm in diameter); single violet-shaped, light pink flowers with darker center; strong stems which curve toward the center to form a compact bouquet above the leaves; profuse flowering; dark green, heart-shaped; flowering 10-11 weeks after planting of unrooted shoot, and by its long lasting and non-dropping flowers.

1 Drawing Sheet

1

The present invention comprises a new and distinct cultivar of African violet plant botanically known as *Saintpaulia ionantha*, and hereinafter referred to by the cultivar name Little Shoshone Girl.

The new cultivar was referred to during the breeding and selection process by the designation 828/1 and is a product of a planned breeding program. The cultivar was originated from a cross made by me in the controlled breeding program in Haffen, Federal Republic of Germany. The female, or seed parent, was a cultivar designated 445/1. The male, or pollen parent, was a cultivar designated 828/3.

Little Shoshone Girl was discovered and selected by me as a flowering plant within the progeny of the stated cross in a controlled environment in Haffen, West Germany. Asexual reproduction of the new cultivar by leaf cuttings, as performed by me at Haffen, West Germany, has demonstrated that the combination of characteristics as herein disclosed for the new cultivar are firmly fixed and retained through successive generations of asexual reproduction.

Little Shoshone Girl has not been observed under all possible environmental conditions. The phenotype may vary significantly with variations in environment such as temperature, light intensity and day length. The following observations, measurements and values describe the new cultivar as grown in a 5.5 cm pot in Haffen, West Germany and Nashville, Tenn. under greenhouse conditions which closely approximate those generally used in commercial practice.

The following traits have been repeatedly observed and are determined to be basic characteristic of Little Shoshone Girl, which in combination distinguish this African violet as a new and distinct cultivar:

- 1) A single crown will not grow larger than 13-15 cm.
- 2) Single, light pink flowers.
- 3) Strong, wirelike and upright flower stems curving toward the center.
- 4) First flush of flowers forms a tight bouquet above the leaves.
- 5) Profuse flowering.
- 6) Each plant carries 5-7 and more upright flower stems each of which carries 7-10 and more flowers.
- 7) Long lasting, non-dropping flowers.

2

8) Plant saleable 10 to 11 weeks after planting of unrooted shoot.

9) Seed capsules push slightly through.

10) Dark green, hairy leaves.

11) Heart-shaped leaves are 3.5 to 4.0 cm in size.

12) After maturity the flowers dry off, and remain on the peduncle without becoming infected by botrytis.

The accompanying color photographic drawing shows a typical specimen plant of the new cultivar grown in a 5.5 cm pot. The colors appearing in the photograph are as true as possible with color illustrations of this type.

In the following description, color references are made to the Royal Horticultural Society Colour Chart (R.H.S.), except where general colors of ordinary significance are referred to. Color values were taken under natural sunlight conditions at approximately 12 p.m. in Nashville, Tenn.

Botanical Classification: *Saintpaulia ionantha*, Ramat., c.v. Little Shoshone Girl.

Parentage:

Male parent.—828/3.

Female parent.—445/1.

Propagation: The new cultivar holds its distinguishing characteristics through successive propagations, by leaf cuttings.

Plant: From 6 cm to 9 cm tall when grown in pots, and 13-15 cm in diameter when fully grown.

Leaves.—General form: Heart-shaped. Diameter: 34-38 mm wide and 36-42 mm long. Texture: Leatherlike. Aspect: Hairy, shiny, slightly serrated. Veins: Uppercide: visible; underside: well pronounced, light green, shiny. Color (upper-side): Yellow-green group 147 A and darker. Color (underside): Greyed-purple group 186 A to B. Petiole: Strong, purplish red, hairy.

Flowers.—Buds: Size: 6-7 mm just before opening.

Shape: Bell-shaped. Color: Pinkish green. Sepals: Five (5). Color: Purplish red. Calyx: Shape: Funnel-shaped. Aspect: Spear-shaped, hairy. Peduncle: Character: Strong upright, hairy. Color: Purplish red. Individual flowers: Size: 33-36 mm. Shape: Single violet-shaped (3 large, 2 small petals). Color (upper-side): Purple group 75 C to D, center purple group 78 A to B. Under cooler

temperatures and more intensive lighting, the pink tends to intensify. Color (underside): Purple group 75 D to C. Borne: Each flower stem carries 7-10 and more flowers on strong, upright peduncles that are free standing above the leaves, thereby forming a compact bouquet. Flowering habit: Flowers 10-11 weeks after planting an unrooted plantlet.

Reproductive organs.—Stamens: Two (2). Anthers: 2 composed of 4 anther cells, seed capsule pushes 10 slightly through. Filaments: Yellowish green, 3-4 mm long. Styles: 6-7 mm long, light pink, base of ovary light green and hairy.

Roots.—Normally developed, white when young, turning slightly brownish when older.

Disease resistance: Up to date, Little Shoshone Girl has shown very good resistance to all major violet diseases.

General observations: Little Shoshone Girl is a mid-size violet, a size between a regular violet (grown in a 10 cm pot) and a superminiature (grown in a 4 cm pot).

Little Shoshone Girl is designed to be grown in a 5.5

cm to 6 cm pot and will not grow larger than 13-15 cm. A nice bouquet of flowers free standing above the leaves develops 10-11 weeks after planting an unrooted plantlet. Each of the 5-7 and more strong flower stems carries 7-10 and more single violet-shaped, light pink flowers with darker center. The flowers are long-lasting and non-dropping. The dark green leaves are heart-shaped and slightly serrated.

I claim:

1. A new and distinct cultivar of African violet named Little Shoshone Girl, as described and illustrated, and particularly characterized by its mid-size growth habit (13-15 cm in diameter); single violet-shaped, light pink flowers with darker center; strong stems which curve toward the center to form a compact bouquet above the leaves; profuse flowering; dark green, heart-shaped; flowering 10-11 weeks after planting of unrooted shoot, and by its long lasting and non-dropping flowers.
